Yucaipa, Calif. 92399

Filed Dec. 26, 1967, Ser. No. 9,931

Term of patent 14 years

(Cl. D48—4)

FIG. 1.

FIG. 3.

FIG. 2.

The phantom line illustrations of a wall plaque, and fragmentary portion of an electric cord, for the lamp fixture are included for illustrative purposes only.

I claim:

The ornamental design for a lamp fixture, substantially as shown and described.
